PIN FASTENING MEANS

Vernon E. Budlong, Brainerd, Minn.

Application February 13, 1947, Serial No. 728,236

1 Claim. (Cl. 24—160)

1

This invention relates to a mounting for a compass, which is particularly adapted to mount the compass on a garment, whereby the compass is retained in a horizontal position at all times to give the user thereof a full view of the compass while walking.

Another object of the invention is to provide a mounting that is simple, easily attached and detached from a garment, and once attached, will remain securely in place without danger of loss of the compass.

With the above and other objects and advantages in view, the invention consists of the novel details of construction, arrangement and combination of parts more fully hereinafter described, claimed and illustrated in the accompanying drawing in which:

Figure 1 is a front elevational view of an embodiment of the invention;

Figure 2 is a side elevational view thereof;

Figure 3 is a rear elevational view of the device;

Figure 4 is a top plan view thereof;

Figure 5 is a bottom plan view and

Figure 6 is a sectional view on the line 6—6 of Figure 1.

Referring more in detail to the drawing, the bracket or mounting embodying the invention is generally designated by the reference numeral 10, and comprises a body 11, having the vertical portion 12 and circular shaped horizontal compass mounting portion 13 extending at right angles to the portion 12, and formed integral therewith. Secured to the portion 13 by suitable fasteners 14 is a conventional compass 15. Formed integral with the body and extending rearwardly of the portion 11 are a pair of opposed apertured ears 16 which mount the U-shaped pin 17 in pivotal relation to the body 11. The pin 17 is provided with pointed ends 18 in the conventional manner, and the pointed ends are receivable in the inturned curved keepers 19 formed on the lower end of the portion 12 in opposed open face relation to each other.

Secured to the front face of the portion 12 by a fastener 20 is the straight portion 21 of the spring latch 22, having the horizontal portion 23 on the end of the portion 21 at right angles thereto, and the depending portion 24 on the outer end of the portion 23 at right angles thereto. The portion 23 extends through the opening 25 in the portion 12 and extending between the inner ends of the keepers 19, retains the pointed ends 18 of the pin 17 in the keepers 19. To release the ends 18, the latch 22 is pushed rearwardly until the pin 17 can be disengaged from the keepers 19.

In use the pin is inserted into a garment so

that the compass 15 is in a horizontal position, and in view for the easy reading thereof. The ends of the pin 17 are then pushed into the keepers, and the spring latch will retain the ends in the keepers until the ends are released from the keepers for the unfastening of the mounting, from the garment.

It is believed that from the foregoing description, the operation and construction of the invention will be apparent to those skilled in the art, and it is to be understood that changes in the minor details of construction may be resorted to, provided they fall within the spirit of the invention, and the scope of the appended claim.

Having thus described the invention, what is claimed as new and desired to be secured by Letters Patent is:

A mounting of the character described comprising a body having a horizontal mounting portion and a vertical supporting portion having an opening in the lower end thereof, a pair of opposed apertured ears formed integral with the vertical portion and extending rearwardly of said portion at the upper end thereof, a U-shaped double pointed pin pivotally mounted at its bight in said ears, a pair of inturned curved keepers formed on the lower end of said vertical portion in opposed open face relation to each other and adapted to engage the pointed ends of said pins and to overlie the opening in said vertical portion, a spring latch having a straight portion fixed to the front face of the vertical portion, a horizontal portion on the lower end of the straight portion extending through the opening in the vertical portion of the body and a depending portion on the lower end of the horizontal portion of the latch engaging the pointed ends of the pin to retain the pins in the keepers.
